UNITED STATES PATENT OFFICE

2,489,515

BUILDING VENTILATOR HAVING AIR INLETS AND OUTLETS

Robert E. Blake, Paul Grange, and Walter L. Thomas, Mason City, Iowa, assignors to Northco Insulating and Ventilating Co., Mason City, Iowa, a corporation of Iowa

Application October 9, 1946, Serial No. 702,322

5 Claims. (Cl. 98—33)

1

The instant invention relates to certain new and useful improvements in ventilating devices and apparatuses such as are used for ventilating and de-humidifying in buildings such, for example, as homes and the like, but is primarily adapted to be used in warehouses, garages, barns, chicken and hog houses, corn cribs, and the like.

By way of introduction, it is to be pointed out that the invention herein disclosed and claimed appertains, in particular, to a similarly constructed and functioning ventilator covered in our copending application, Serial No. 574,382, filed on January 24, 1945, now Patent 2,433,544. More specifically, the improvements have to do with an auxiliary air intake arrangement forming a part of a conduit, which conduit is divided into coating ducts, one for purposes of picking up and delivering atmospheric air into the barn or other enclosure, and the other of which is adapted to suck the air out of the enclosure space and to carry it, under pressure, to the exterior of the enclosure.

Being an improvement upon the structure in the copending application, the structure utilized bears certain basic resemblances thereto in that we utilize a conduit which is expressly made in a manner to suitably handle the moist, foul air discharge, this being governed by screened intake openings in one duct of the conduit, the latter duct having a motor-driven fan unit located therein and suitably sized to handle the movement of air necessary.

Stated with greater particularity, we have evolved and produced a simple and expedient wooden, or equivalent conduit arrangement which spans the upper space in the enclosure at a point below the ceiling and which opens through one end of the enclosure or building for purposes of taking in atmospheric air, and opens through another end of the building at its opposite end for purposes of scavenging the air, whereby to set up a suitable circulation to satisfactorily achieve the ends sought.

Other objects, features and advantages of the invention will become more readily apparent from the following description and the accompanying illustrative drawings.

In the drawings, wherein like numerals are employed to designate like parts throughout the views:

Figure 1 is a perspective view of a barn, building or other enclosure provided with ventilating means constructed in accordance with the principles of the present invention.

Figure 2 is a central longitudinal sectional view of the same structure, this to bring out the details of construction and the arrangement of such details.

Figures 3 and 4 are transverse sectional views

taken on the planes of the lines 3—3 and 4—4, respectively, of Figure 2.

By way of further explanation, it is to be pointed out that the invention is applicable to any space in which the same might be satisfactorily employed for de-humidifying and ventilating purposes. In the drawings, it is sufficient to simply show what may be called a building or perhaps a barn A, with parallel side walls B—C, end walls D—E, and roof F. Considered as a unit, the invention is, broadly, a wooden or equivalent conduit 6. The over-all length of the conduit corresponds to the length of the space in which it is located. In the instant situation, it is shown positioned in the upper area of a barn just beneath the ceiling. As brought out in Figure 4, the conduit comprises top and bottom boards 7 and 8 and side boards 9 and 10, these being secured together in box-like relationship, and reinforcing strips of wood or the like 11 being arranged for assembling and securing the parts together. A central partition 12 serves to define upper and lower main and auxiliary ducts 13 and 14, respectively. Observing the ducts, it will be noted that the main duct is closed at the right-hand end, as indicated at 15, and at the opposite end is enlarged and flared into funnel-shaped form, as at 16. Here it is provided with an extension sleeve 17 whose discharge end extends through an opening in the end wall D, as shown in Figure 2, and is flanged and secured in place as at 18. This sleeve serves as an adapter housing for a stand or bracket 19 which serves to support a suitable electric motor 20 for driving a suction or exhaust fan 21. The fan is located within the confines of the sleeve and the outer end of the sleeve is provided with freely hinged louvers 22. These louvers are normally closed. When, however, the fan is in operation, the louvers are swung to open position and the accumulated air and moisture in the duct or space 13 is scavenged and discharged into the atmosphere on the outside of the building. It will be noted that the auxiliary air intake duct is somewhat shorter in length than the main duct 13, that it opens through the wall E at the right-hand end, where it is provided with an intake hood of downturned visor-like form, as indicated at 22. This auxiliary duct 14 is closed at the left-hand end, as indicated at 23. Also, this duct is provided with air intake holes or ports 24 covered by suitable screens 25. The other or main duct 13 is provided with intake openings 26 covered by suitable screens 27.

In operation, it is obvious that the suction created within the space of the barn produces a "pull" on the screened intake ports 24. Thus, air is sucked from the exterior of the barn, as shown by the arrows in Figure 1. The incoming air escapes through the screened openings 24 and

circulates around in the barn and is then drawn, by suction from the fan, into the duct 13, this by way of screens 27 and openings 26. The air from the atmosphere is thus drawn in, circulated, and then carried out through the duct 13 and the fan pushes the louvers 24 open, discharging said foul and moist air again into the atmosphere. The invention has to do with the simplicity of the two ducts in the one conduit and the simple choice, selection and arrangement of details which go to make up such conduit.

In view of the foregoing description taken in conjunction with the accompanying drawings, it is believed that a clear understanding of the construction, operation and advantages of the device will be quite apparent to those skilled in this art. A more detailed description is accordingly deemed unnecessary.

It is to be understood, however, that even though we have herein shown and described a preferred embodiment of our invention that the same is susceptible to certain changes fully comprehended by the spirit of the invention as herein described and within the scope of the appended claims.

We claim:

1. In a structure of the class described, in combination, a building construction defining a room, storage or equivalent space, a horizontally arranged conduit open at opposite ends and having said ends in communication with openings in opposite end walls of the building construction, a partition in and extending longitudinally of said conduit and dividing the latter into separate intake and exhaust passages, the latter having individual screened openings, the inlet end of the air intake passage being provided with a downturned hood-like adapter located exteriorly of said building construction, the discharge end of the exhaust passage being enlarged and provided with a sleeve having pressure-opened normally-closed louvers therein, and an electric motor driven fan mounted in said sleeve, whereby to create a suction within said space, to suck foul and moist air from said space and to exhaust same to the atmosphere and to create sufficient suction on the screened openings in the intake passage to facilitate the delivery of air into the latter.

2. Ventilating and de-humidifying means for warehouses, barns and the like comprising, in combination, a building embodying a room, storage or equivalent space and including a ceiling, a horizontally situated conduit supported for use in said space close to, but spaced from, said ceiling and having its opposite ends open and opening through opposite end walls of said building construction, a partition in and extending longitudinally of said conduit and dividing the latter into a lower fresh-air intake and distributing passage, and an upper foul air exhausting passage, the intake passage being closed at its inner end and of a cross-section less than the cross-section of the exhausting passage, the inlet end of said air intake passage being provided with a downturned air intake hood, the latter located exteriorly of the adjacent building wall, the discharge end of the exhausting passage being gradually enlarged in a direction toward the adjacent building wall, a flanged sleeve fitted into an opening in the last named wall and in communicative connection with the adjacent en-

larged end of said exhausting passage, an electric motor driven fan mounted in said sleeve, the underside of said air intake passage being provided with longitudinally spaced ports and individual screens covering said ports, the top side of said exhausting passage being also provided with ports covered by individual screens.

3. The structure specified in claim 2, together with louvers mounted in the discharge end of said sleeve at a point outwardly of the fan, said louvers being closed when the fan is still, and automatically opened when the fan is in operation.

4. A room space ventilator of the type herein shown and described comprising a main conduit embodying top, bottom and side walls, closed at one end, enlarged, flared and open at the opposite end, said top wall being provided with screened openings, an auxiliary conduit attached to and located in alignment beneath the bottom wall of said main conduit, said auxiliary conduit being smaller in cross-section and area than the main conduit, closed at its inner end and open at its outer end, the closed inner end being spaced inwardly from the flared open end of the main conduit, the bottom of said auxiliary conduit having screened air inlet openings, a downturned air intake hood attached to the intake end of said auxiliary conduit, said hood being open at its bottom.

5. A room space ventilator of the type herein shown and described comprising a main conduit embodying top, bottom and side walls, closed at one end, enlarged, flared and open at the opposite end, said top wall being provided with screened openings, an auxiliary conduit attached to and located in alignment beneath the bottom wall of said main conduit, said auxiliary conduit being smaller in cross-section and area than the main conduit, closed at its inner end and open at its outer end, the closed inner end being spaced inwardly from the flared open end of the main conduit, the bottom of said auxiliary conduit having screened air inlet openings, a downturned air intake hood attached to the intake end of said auxiliary conduit, said hood being open at its bottom, a flanged sleeve adapted to be fitted into an opening in a building wall, the inner end of said sleeve being connected to the discharge end of said main conduit, the outer end portion of said sleeve being provided with gravity closed, pressure opened louvers, a stand mounted in said sleeve, a motor mounted on said stand, and a fan operatively connected with the motor and located between the motor and the louvers.
